Primary Examiner—Adir Aronovich

(74) Attorney, Agent, or Firm—Beyer Weaver & Thomas, LLP

(57) **CLAIM**

The ornamental design for a camera, substantially as shown and described.

DESCRIPTION

FIG. 1 is a perspective view of a camera showing our new design;

FIG. 2 is a left side view for the camera shown in FIG. 1.

FIG. 3 is a right side view for the camera shown in FIG. 1.

FIG. 4 is a rear view for the camera shown in FIG. 1.

FIG. 5 is a front view for the camera shown in FIG. 1.

FIG. 6 is a top view for the camera shown in FIG. 1.

FIG. 7 is a bottom view for the camera shown in FIG. 1.

FIG. 8 is a perspective view of the camera shown in FIG. 1. The camera is placed in a camera stand shown in broken lines for illustrative purposes only and forms no part of the claimed design; and,

FIG. 9 is a second embodiment of the camera shown in FIG. 1 where the apertures and knurled surfaces are illustrated in broken lines and form no part of the claimed design.

The broken lines shown throughout the drawings are for illustrative purposes only and form no part of the claimed design.

1 Claim, 6 Drawing Sheets
